(57) **CLAIM**

The ornamental design for a marine sensor platform, as shown and described.

DESCRIPTION

This invention was made with government support under grant no. DE-AR0000514 awarded by the U.S. Department of Energy (ARPA-E). The government may have certain rights in the invention.

FIG. 1 is an upper perspective view of a marine sensor platform, showing the new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed lines and structure they depict form no part of the claimed design.
